US00D913199S

(12) **United States Design Patent** (10) Patent No.: **US D913,199 S**
Song et al. (45) Date of Patent: **** Mar. 16, 2021**

(54) **CONTROL AND INDICATOR PANEL FOR VEHICLES**

(71) Applicant: **LG Electronics Inc.**, Seoul (KR)

(72) Inventors: **Seunghwan Song**, Seoul (KR); **Seungmo Kang**, Seoul (KR); **Hansoo Kim**, Seoul (KR)

(73) Assignee: **LG ELECTRONICS INC.**, Seoul (KR)

(**) Term: **15 Years**

(21) Appl. No.: **35/507,427**

(22) Filed: **Mar. 6, 2019**

(80) **Hague Agreement Data**

Int. Filing Date: **Mar. 6, 2019**

Int. Reg. No.: **DM/202716**

Int. Reg. Date: **Mar. 6, 2019**

Int. Reg. Pub. Date: **Sep. 13, 2019**

(30) **Foreign Application Priority Data**

Sep. 10, 2018 (KR) 30-2018-0042130

(57) **CLAIM**

The ornamental design for control and indicator panel for vehicles, as shown and described.

DESCRIPTION

1. Control and indicator panel for vehicles

1.1 : Perspective

1.2 : Front

1.3 : Back

1.4 : Left

1.5 : Right

1.6 : Top

1.7 : Bottom

The broken lines depict portions of a control and indicator panel for vehicles that form no part of the claimed design; the fine lines on the drawings indicate the flat surface, curved surface or display part; reproduction 1.1 is a front perspective view of the control and indicator panel for vehicles; reproduction 1.2 is a front view thereof; reproduction 1.3 is a back view thereof; reproduction 1.4 is a left view

(Continued)

thereof; reproduction **1.5** is a right view thereof; reproduction **1.6** is a top view thereof; and reproduction **1.7** is a bottom view thereof.

1 Claim, 7 Drawing Sheets
